UNITED STATES PATENT OFFICE.

ENÉAS GUIMARÃES MASCARENHAS, OF JUIZ DE FORA, BRAZIL.

AUTOMATIC TRAIN-STOP SYSTEM.

1,119,620.

Specification of Letters Patent.

Patented Dec. 1, 1914.

Application filed June 22, 1913. Serial No. 775,464.

To all whom it may concern:

Be it known that I, ENÉAS G. MASCARENHAS, a subject of the Republic of Brazil, and a resident of Juiz de Fora, Estado de Minas, Brazil, South America, have invented a new and Improved Automatic Train-Stop System, of which the following is a full, clear, and exact description.

This invention relates to an automatic train stopping apparatus adapted for use in connection with a block signal system, whereby a train is automatically stopped or slowed down or a signal given when a train enters a block already occupied by another train and a stop signal is disregarded, or when the train travels at excessively high speed or when part of the circuit is interrupted or deranged for any reason.

The invention has for its general object to improve and simplify the construction and operation of train stopping systems of the character referred to, so as to be extremely reliable in use, comparatively inexpensive to install and keep in order, and so designed as to arrest the movement of trains under a variety of emergency conditions so as to avoid accidents.

Another object of the invention is the provision of a stop circuit carried by the train which controls the operation of an air brake valve or a throttle valve in case the locomotive is steam driven, or a circuit breaker in case the locomotive is electrically driven, such stop circuit being controlled by a normally energized relay whose circuit is kept closed as long as normal conditions prevail.

Another object of the invention is the provision of a stop system including a relay circuit that is normally closed during the passage of the train through a block by circuit closers on the train which are adapted to open by means of contact rails as the train enters or leaves the block, so that the relay will be connected by contact shoes engaging the said contact rails in order to complete the relay circuit in case the block is clear or to break the relay circuit by an open switch operatively connected with the block signal when the signal is up or in danger position, with the result that the de-energizing of the relay causes the train stop to become effective for arresting the movement of the train.

Another object of the invention is the provision of a speed responsive relay shunting device for establishing a shunt around the

contacts of the relay for the purpose of rendering the stop circuits operative for arresting the movement of the train when the speed exceeds a predetermined limit.

Another object is the provision of a signal circuit which is closed to energize a signal as the train passes the contact rails, whereby the engineer will be informed that it is proper to proceed; and associated with the signal system is an electro-magnetically operated element which co-operates with the speed responsive relay shunting device in order to stop the train if the speed exceeds a given point at the time the train passes the contact rails at the end of the block.

An additional object is the provision of a lock-out device for holding the contacts of the stop circuit controlled relay in open-circuit position when the engine is traveling at a low rate of speed; even while the block is controlled by another train.

With these objects in view, and others as will appear as the description proceeds, the invention comprises various novel features of construction and arrangement of parts which will be more fully described herein-after and set forth with particularity in the claims appended hereto.

In the accompanying drawings, which illustrate certain embodiments of the invention, and wherein similar reference characters are employed to designate corresponding parts throughout the several views, Fig. 1 is a diagrammatic view of the various devices and the circuit connections carried by the locomotive, and showing the parts in the position they occupy while the train is traveling under normal conditions through a block; Fig. 2 is a diagrammatic view of the speed responsive relay shunting device and relay contact, the position of the parts representing the train as standing; Fig. 3 is a view similar to Fig. 1, but showing the contact shoes engaged with the contact rails and the track circuits in relation to the train circuits; Fig. 4 is a diagrammatic view similar to Fig. 3, but representing an emergency condition when the stop device has been set to stop the train; the emergency condition being the presence of another train in the block which the arrested train has entered; Fig. 5 is a diagrammatic view showing the system modified in regard to the stop circuit being normally closed instead of normally open, as in the previous figures; Fig. 6 is a view similar to Fig. 5,

showing the stop device released for the stopping of the train; and Fig. 7 is a dia-

grammatic view showing the arrangement of the blocks into which the track is divided.

Referring to Fig. 7 of the drawings, A, B and C designate three of the blocks into which a track is divided, and the respective blocks have a source of current 1 connected with the rails a, a', b, b', c, c' , and connected across the rails of each block is a relay 2 or equivalent means that is constantly energized as long as a train is not in the block to short circuit by its axles the source of current 1. When the source of current is short-circuited the relay 2 becomes deenergized so that the semaphore or other block signal 3 will move to danger or horizontal position, such signal being normally kept in down or clear position by a solenoid 4 or equivalent means which has one terminal connected by a wire 5 with a battery or other source of current 6 which has a grounded terminal 7 whereby the circuit is completed to the grounded terminal 8 of the solenoid 4, there being in the wire 5 the fixed and movable contacts 9 and 10 of the relay. At one end of each block are contact rails r and r' which are normally electrically connected together by wires 11 and 12, and fixed and movable contacts 13 and 14, the movable contact 14 being connected with the movable contact 10 of the relay 2 so that when the semaphore is in danger position, by reason of a train being in the block, the contact rails will be disconnected, so that, should another train enter the block, the stop circuit thereof would be so influenced by the rails r and r' being disconnected that the entering train would be arrested. In the present instance a stop device is applied to the air brake system so as to cause the brakes to set under emergency or abnormal conditions, but it is to be understood that the stop device could be applied to the throttle of the locomotive when the latter is steam driven, or could be applied to open the circuit of the propelling motors in an electric locomotive. In the drawings 15 designates the brake pipe in which is arranged a valve 16 having on its stem a sector 17 to which is fastened at 18 a flexible element 19 that engages the periphery of the sector 17, and connected with this element 19 is a spring or other motor 20 which tends to move the valve to a position for causing the brakes to set. A latch 21 normally engages a finger or equivalent means 22 on the sector 17, and this latch carries an armature 23 which is attracted by an electro-magnet 24 when the latter is energized, so that the latch 21 will be released to permit the sector 17, element 19 and spring 20 to open the valve 16. This electro-magnet 24 is in a stop circuit consisting of the wires 25, 26 and 27, there being between the wires 25

and 26 a source of current 28, and between the wires 26 and 27 a movable and a fixed contact 29 and 30 of the controlling relay 31. The contacts 29 and 30 of the relay 31 are normally separated so that the stop circuit will be open, and to effect this result the relay 31 is energized as long as conditions are normal.

The relay circuit is carried wholly by the train while the latter is at any point in the block except where the contact rails r and r' are located, and when the train is at the contact rails the relay circuit will have a portion located in the track, and as long as the block is clear and the said track portion of the circuit is intact the relay circuit will remain completed so that the stop device will not be actuated. In Fig. 1 the circuit of the relay 31 is shown closed by the closing portion carried by the train, such closing portion consisting of circuit closers 32 and 33 and the connecting wire 34. The movable members 35 of the circuit closers are electrically connected with the supporting plates or brackets 36 which are respectively connected by wires 37 and 38 to the relay 31, there being included in one of the wires the battery or other source of current 39. The movable members 35 carry springs 40 which are adapted to engage the fixed contacts 35^a on the circuit breakers, and it is to these contacts 35^a that the wire 34 is connected. When the parts are in the position shown in Fig. 1 the current passes through a path consisting of the battery 39, wire 37, relay 31, wire 38, circuit breaker 33, wire 34, circuit breaker 32 and wire 37.

The movable members 35 of the circuit breakers 32 and 33 are in the form of first class levers pivoted at 41 to the brackets 36 and the outer ends of the respective levers, which, like the brackets 36, are made of metal to form conductors, carry metallic shoes 42 and 42' which are adapted to engage the contact rails r and r' , as shown in Fig. 3, so as to separate the contacts of the circuit breakers 32 and 33. When the contact shoes 42 and 42' engage the rails r and r' the relay 31 has its circuit completed by a portion installed in the track, said portion consisting of the rails r and r' , wires 11 and 12 and contacts 13 and 14, so that the complete circuit consists of the relay 31, wire 38, right bracket 36, right lever 35, shoe 42', rail r' , wire 11, contacts 13 and 14, wire 12, contact rail r , shoe 42, left lever 35, left bracket 36, wire 37, battery 39 and relay 31. The flow of current through this path continues as long as the shoes 42 and 42' are in contact with the rails r and r' . If there happens to be a train in the same block the external circuit of the relay will be open as shown in Fig. 4, by reason of the contact 14 being separated from the contact 13, this being brought about by the relay 2 being short

circuited by the train T represented by an axle and wheels thereon. The current from the block battery 1 flows from the battery to one rail of the track, thence through the 5 axles of the train T, through the other rail and back to the battery. Sufficient current does not flow through the track relay 2 to fully energize the same and maintain the contacts 13 and 14 engaged, and at the same 10 time the contacts 13 and 14 also separate the contacts 9 and 10 of the relay 2 to open the circuit of the solenoid 4 to actuate the semaphore. Thus the train T is warned that the block is occupied by another train, and 15 should the train T attempt to pass the semaphore without stopping or slackening the speed the stop circuit will be completed by the deenergizing of the relay 31, with the result that the air brakes will be set, since the 20 completing of the stop circuit energizes the electro-magnet 24, which in turn releases the latch 21 from the air brake valve actuating means, so that such means can move from a 25 position shown in Figs. 2 and 3 to the position shown in Fig. 4. If the engineer sees the semaphore and wishes to prevent the train stop from operating, the stop circuit can be opened by means of a hand-operated switch 43. All the parts of the apparatus 30 are automatically reset after being actuated with the exception of the air brake valve 16, which must be reset by hand, and in doing so the sector 17 is moved in an anti-clockwise direction so as to engage the finger 22 with 35 the latch 21.

In order to prevent the train from attaining a speed beyond a predetermined point a speed responsive relay shunting device is employed, such device consisting of a movable contact 42, which is connected by a wire 48 to the wire 27, and which is adapted to engage a contact 44 that is connected by a wire 45 with the wire 26, so that the contacts 42 and 44 and wires 43 and 45 form a shunt around the contacts 29 and 30 of the relay 31. The movable contact 42 is operatively connected with a centrifugal governor or speed responsive device D which has its shaft 46 connected by a sprocket chain or equivalent drive with an axle of the locomotive or some other moving part, the balls 48 of the device D being connected with a longitudinally movable rod 49 that is in turn connected with the movable contact 42. When the speed becomes sufficiently high as to engage the contact 42 with the contacts 44 the stop circuit will be closed, so that the electro-magnet 24 will release the latch 21 from the brake valve actuating means. It may be desirable to prevent the stop circuit from closing when it otherwise would be closed by the deenergizing of the relay 31 when the contact rails r and r' are disconnected by the presence of another train in the block. For this purpose a lock-

out device for the movable contact 29 of the relay 31 is provided, such lock-out device consisting of an extension 50 on the rod 49 so arranged as to extend under or engage the tip 51 of the contact 29 when the speed 70 of the train is sufficiently low. By this means the engineer can continue to move slowly into the block without the engine being stopped. In this way unnecessary delays are prevented and the speed of the train 75 can be quickly increased as soon as the track ahead is clear.

When the shoes 42 and 42' strike the contact rails r and r' a signal circuit is closed, which circuit includes a pair of circuit 80 closers s and s' that have their adjustable contacts 52 connected together by a wire 53, while the movable contacts 54 are respectively connected by wires 55 and 56 with a bell or other signal 57 suitably arranged to 85 attract the attention of the engineer to the semaphore. The circuit closers s and s' are associated with the circuit closers 32 and 33, but insulated from the latter, and in fact the movable contacts 54 of the circuit closers s 90 and s' are carried by the levers 35 from which they are insulated so that the engagement of the shoes 42 and 42' with the rails r and r' will perform three functions; first, they will connect the relay 31 with the portion of the circuit installed in the track; second, they will open the circuit closers 32 and 33, and third, they will close the circuit closers s and s'. When the shoes 42 and 42' are out of engagement with the contact 95 rails r and r', the circuit closers 32 and 33 will be maintained in closed position, and the circuit closers s and s' in open position by springs 58 or equivalent means acting on the levers 35. It may be desirable to compel 100 the engine to automatically stop at a lower maximum speed when the train enters a block than is possible with the speed responsive device D when the train is traveling through the block beyond the contact rails 105 r and r'. For this purpose means is provided for shifting the contact 44 in the shunt that bridges the relay 31. Such shifting means consists of an electro-magnet 60 which is connected by wires 61 and 62 to the wires 55 and 56, so that, when the circuit 110 closers s and s' are closed, the electro-magnet 60 will be energized at the same time the signal or bell 57 is energized. This energizing of the magnet 60 moves the contact 44 from the position shown in Fig. 1 to the 115 position shown in Fig. 3, so that the contact 42 will engage the contact 44 somewhat earlier in the acceleration of the speed of the train than when the contact 44 is held 120 in its fully retracted position by the spring 63.

In the system hereinbefore described the stop circuit is normally opened, but it may be desirable to employ a normally closed 130

stop circuit, and for this purpose the electro-magnet 24 normally holds in raised position a weight or hammer 66 which is adapted to strike, when the electro-magnet 24 is deenergized, a latch 67 to release it from the finger 22 of the brake valve actuating means. The stop circuit controlling relay 31 acts on this armature or movable contact 29 in such a manner as to normally engage the fixed contacts 30 and at low speeds the device 50 serves to maintain the contacts 29 and 30 in engagement in case the relay 31 is deenergized by the presence of another train in the block. A slider or bodily movable contact 68 is operatively connected with the reciprocating rod 49 of the speed responsive device D. This sliding contact 68 is adapted to engage fixed contacts 69 and 70 which normally form with the slider 68 a part of the stop circuit, the slider being in the position shown by dotted lines, Fig. 5, when the train is not moving. Coöperating with the slider 68 is a movable contact 71 carrying an armature 72 which is adapted to be attracted by the electro-magnet 60 when the bell circuit is closed, thereby opening the stop circuit at a time when the train is traveling at such a speed that the slider is out of engagement with the contact 69, as shown in Fig. 6. In case the train attains a dangerously high speed the slider 68 will move so far to the right, Fig. 5, that the insulation 74 will pass under the contact 71 and open the stop circuit. Of course when the extension 50 is retracted from the contact 29, the stop circuit can be opened by deenergizing the relay 31 when another train in the block has opened the circuit by disconnecting the contact rails r and r' . From the foregoing description taken in connection with the accompanying drawings, the advantages of the method of operation and of the apparatus shown will be readily understood by those skilled in the art to which the invention appertains, and while I have described the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. In a train stop system, the combination of a block consisting of track rails, a source of current connected with the rails, contact rails and an electric device connected with the track rails for electrically connecting the contact rails together and adapted to be deenergized by the axles of the train short-circuiting the said source of current for causing the contact rails to be disconnected, a stop circuit on the train, a

normally energized relay including contacts controlling the stop circuit, a shunt around the contacts, means for opening the normally closed relay circuit and connecting the relay with the contact rails whereby the relay is maintained energized when the contact rails are electrically connected and is deenergized when the contact rails are disconnected, and a speed responsive device adapted to control the shunt and the contacts of the relay for controlling the stop circuit independently of the relay when the speed of the train reaches a predetermined rate.

2. In a train stop system, the combination of a block consisting of track rails, a source of current connected with the rails, contact rails and an electric device connected with the track rails for electrically connecting the contact rails together and adapted to be deenergized by the axles of the train short-circuiting the said source of current for causing the contact rails to be disconnected, a stop circuit on the train, a normally energized relay controlling the stop circuit, means for opening the normally closed relay circuit and connecting the relay with the contact rails whereby the relay is maintained energized when the contact rails are electrically connected and is deenergized when the contact rails are disconnected, a speed responsive device for controlling the stop circuit independently of the relay when the speed of the train reaches a predetermined rate, and means actuated by the speed responsive device for preventing the relay from controlling the stop circuit when the speed of the train is below a predetermined point.

3. In a system of the class described, the combination of a pair of contact rails, a controlling circuit including a pair of circuit breakers each having a movable member moved to open circuit position by a contact rail, a switch controlled by the presence of a train in a block for connecting or disconnecting the contact rails, a shoe on each movable member for engaging a contact rail to complete the controlling circuit through the rails and said switch, means for closing the circuit closers when the shoes move out of engagement with the contact rails, another controlling circuit, and normally open circuit closers arranged to be closed by the shoes engaging the said contact rails.

4. In a system of the class described, the combination of a normally closed relay circuit carried by a train and adapted to be opened by another controlling train, a speed responsive device including a movable element, and a stop circuit including a switch controlled mechanically by the said element of the speed responsive device or electrically by the relay circuit.

5. In a system of the class described, the combination of a train stop circuit, a relay having its contacts connected with the circuit and normally separated, a normally open shunt around the said contacts, and speed responsive means for closing the shunt to energize the stop circuit independently of the relay.
6. In a system of the class described, the combination of a train stop circuit, a relay having its contacts connected with the circuit and normally separated, a normally open shunt around the said contacts, said shunt including separately movable contacts, a speed responsive device for moving one contact for closing the shunt at a predetermined rate of speed of the train, and means for moving the other contact for closing the shunt at a lower speed.
7. In a system of the class described, the combination of a train stop circuit, a relay having its contacts connected with the circuit and normally separated, a normally open shunt around the said contacts, said shunt including separately movable contacts, a speed responsive device for moving one contact for closing the shunt at a predetermined rate of speed of the train, an electro-magnet for moving the other contact to close the shunt at a lower speed, and means on the track for controlling the circuit for the said electro-magnet.
8. In a system of the class described, the combination of a stop circuit including an electro-magnet, a train stop device controlled by the electro-magnet, a relay normally energized, means whereby said relay is deenergized when the train is in the controlling range of another train, the contacts of the relay being connected with the stop circuit and normally separated, and an automatically actuated lock for holding the contacts out of engagement when the speed is below a certain point.
9. In a system of the class described, the combination of a stop circuit including an electro-magnet, a train stop device controlled by the electro-magnet, a relay normally energized, means whereby said relay is deenergized when the train is in the controlling range of another train, the contacts of the relay being connected with the stop circuit and normally separated, an automatically-actuated lock for holding the contacts out of engagement when the speed is below a certain point, and a speed responsive device for closing the stop circuit when the speed of the train reaches a predetermined point.

In testimony whereof I have signed my name to this specification in the presence of two subscribing witnesses.
